FASTENING DEVICE AND ARTICLE TO BE
FASTENEDArthur Lawton, Cranston, R. I., assignor to Well
Mfg. Corporation, New York, N. Y., a corpora-
tion of New York

Application October 20, 1937, Serial No. 169,951

3 Claims. (Cl. 40—20)

This invention relates to improvements in fastening devices and articles to be fastened.

More specifically the present invention is directed to a clasp or fastening device for securing ornaments, initials, badges, jewelry and such articles on a support such as wearing apparel, hand bags, suit cases and the like.

The device of my present invention is particularly well adapted for use in fastening initials on ladies' hand bags and I shall therefore describe the same in connection with such application, it being understood, of course, that I do not wish to be limited to this or any other specific application of my invention.

Heretofore in fastening initials on ladies' hand bags the initials were provided with a plurality of prongs, usually four, which were forced through the material of the bag. Great care must be taken in applying such initials to avoid marring the bag and the lining, special tools must be employed and great skill exerted in clenching these prongs beneath the fabric of the lining. As a result of the skill required the fastening of such initials has been left to those trained in such work.

It is an object of the present invention to provide a fastening device which can be readily applied to an article such as hand bag initials, for example, to firmly secure the same to its support by the user of the bag without the use of any tools and without the danger of marring the fabric of the bag.

Another object of the present invention resides in the provision of cooperating means on the article to be fastened whereby the article will be held close to the support and when once fastened will not move or rotate on the support and wherein there are no projections or exposed prongs to scratch or injure the user or the fabric of the support.

Other objects of the present invention will be manifest from the following description and the accompanying drawing, in which drawing:

Fig. 1 is a sectional elevation of my improved device;

Fig. 2 is a plan view of the spring member; and

Fig. 3 is a plan view of the cover plate.

Referring to the drawing in detail: 2 designates a hollow body portion or dome having a plate 4 of spring material inserted therein and supported by the walls thereof. This plate is provided with radially extending intersecting slits 6 which provide spring gripping fingers. Adjacent the plate 4 I also insert in the dome 2 another

plate 8 which may be of the same material as the dome itself. This plate is provided with a central orifice 10 adapted to receive a projecting member or pin 12 having a roughened or threaded surface. It is to be understood that I may employ 5 a threaded screw if desired.

After inserting these two plates 4 and 8 in place I turn the rim of the dome 2 over to provide an annular flange 11 which serves to clamp the plates 4 and 8 in place and firmly to hold 10 the same against the outwardly curved wall of the dome. By simply turning over the rim of the dome 2 against the plate 8 thereby pressing the flat plates against the curved wall of the dome the necessity of forming shoulders or other 15 stops for this purpose in the dome is eliminated.

The fastening pin 12 is carried by the article to be supported, which in the present illustration is an initial 14. In applying this fastening pin or screw 12 to the initial or other article to be 20 fastened, I drill a hole in the material of the initial slightly larger than the head 16 of the pin or screw and after inserting the head of the pin therein I upset the material of the initial about the same to provide an inwardly extending 25 annular flange 18 overlying the head of the pin securely to hold the same in place. By inserting the pin head in the article in this manner I eliminate the necessity of solder which has heretofore been employed for this purpose and which 30 is likely to work loose in time and which results in an uneven surface. By my improved method of fastening the pin in the initial or article a flat unobstructed surface is provided so that the initial will lie flat and snugly against the fabric 35 17 of the support throughout.

In addition to the screw 12 I also employ a pin or stud 20 offset with respect to the pin or screw 12 which is secured to the article in the same manner as the screw 12.

As will be seen from Fig. 3 the plate 8 has a flat annular rim 9 and the central portion is preferably slightly domed or concavo-convex so that there is a space between the fabric 17 of the material of the support and this plate adjacent 45 the flange 11 of the dome 2. As will also be seen from the drawing the stud or pin 20 is so positioned on the article 14 as to be within the confines of the annular flange 11 at the space above mentioned which is provided between flange and 50 the cover plate 8.

The application of the fastening device of the present invention will be readily understood. The initial or other article 14 is placed upon the hand bag or other support at the desired location 55

and with a slight pressure on the article the point of the screw 12 will penetrate the fabric of the support. The dome 2 with the plates 4 and 8 attached thereto is then placed upon this screw 5 and pushed firmly into place, the screw entering the orifice 10 in the plate 8 and being guided thereby into the small hole 7 at the intersection of the slits 6 in the plate 4. The slits 6 will spread causing the four points of the spring metal 10 formed by the intersecting slits to engage the threads on the screw 12 to grip the same and resist withdrawal of the pin. The pointed pin 20 will engage the supporting fabric and also penetrate the same and enter the space provided between the flange 11 and the cover plate 3 as above mentioned.

It will be appreciated that the engagement of the points of the spring plate 4 with the threads of the screw 12 will securely hold the article on its support and that the engagement of the pin 20 with the fabric will serve to prevent rotation of the article on the support once the same is fastened as aforesaid.

It will also be appreciated that by the novel 25 method of fastening the screw 12 in the initial or article the even surface provided thereby will permit the article to closely engage the support.

While I have illustrated and described one embodiment of my invention and one application 30 of the same, it is to be understood that I do not wish to be limited thereto as my invention has manifold applications and various changes and modifications may be made in the structure herein illustrated and described without departing 35 from the spirit and scope of my invention.

What I claim is:—

1. A fastening device comprising in combination a hollow dome-shaped body member, a spring 40 plate having opposed gripping fingers supported in said body member and supported by the curved walls thereof, a cover plate in said body member, said plates being superimposed, said cover plate being provided with a central orifice and its outer face being concavo-convex adjacent said

central orifice and flat adjacent its edge, the edge of said body member having an inwardly turned flange bent over upon the flat edge of said cover plate to clamp both plates between said flange and the inside of the curved wall of 5 said body member.

2. A device of the class described comprising a hollow body member having converging side walls, a spring plate supported within said body member by said side walls, said plate having 10 transverse intersecting slits to provide spring gripping fingers, a cover plate having a flattened annular rim and a concavo-convex central portion, said cover plate being supported by said spring plate and having a central orifice there- 15 in, said body member having its edge folded over upon the flat rim of said cover plate securely to hold both of said plates in said body member and an article supporting a projecting member adapted to be inserted through the orifice of 20 said cover plate and gripped by said fingers.

3. A device of the class described comprising a hollow body member having converging side walls, a spring plate supported within said body member by said side walls, said plate having 25 transverse intersecting slits to provide spring gripping fingers, a cover plate having a flattened annular rim and a concavo-convex central portion, said cover plate being supported by said spring plate and having a central orifice therein. 30 said body member having its edge folded over upon the flattened rim of said cover plate securely to hold both of said plates in said body member and an article supporting a central projecting member and an offset projecting member, 35 said central member adapted to be inserted through the orifice of said cover plate and gripped by said fingers, said offset member being so positioned as to be within the confines of said body member and extending into the space provided 40 between said folded edge of said body portion and the concavo-convex member of said cover plate.

ARTHUR LAWTON.
